UNITED STATES PATENT OFFICE.

WILLIAM JOHNSON CALDER, OF EDINBURGH, SCOTLAND.

CHIMNEY COWL OR TOP.

1,310,470.

Specification of Letters Patent. Patented July 22, 1919.

Application filed January 14, 1919. Serial No. 271,167.

To all whom it may concern:

Be it known that I, WILLIAM JOHNSON CALDER, doctor of medicine, a subject of the King of England, residing at Edinburgh, 5 Scotland, Great Britain, have invented certain new and useful Improvements in Chimney Cowls or Tops, of which the following is a specification.

This invention relates to chimney cowls 10 or tops and its object is to so make the same that down drafts will be prevented.

Under this invention the top consists of a structure of peculiar shape comprising one or more superimposed parts each of a special 15 combined bulbous and conic formation as hereinafter described. Each part has a globular body open at top and bottom so as to form restricted passageways or throats and, forming a continuation of the bottom 20 of the globular body, is an enlargement which is preferably made of a flared or truncated cone formation and is so fitted on, or over, the next globular body as to leave lateral passageways at either side for the escape 25 of any downrush of air. Each globular body may have air escape openings at the opposite sides thereof. The structure may be surmounted by a top of a truncated conic formation upon which a revolving or other 30 cowl is or may be placed.

There may be three globular parts with their depending conic enlargements arranged one above the other. Owing to the special 35 formation of these parts any air rushing downward escapes at either side of the structure.

In order that the invention may be clearly understood I make reference to the accompanying drawings which show, by way of 40 illustration or example, one mode of constructing the chimney cowl or top. In these drawings:—

Figure 1 is a vertical section of the chimney cowl;

Fig. 2 is a cross section on the line A—B, Fig. 1;

Fig. 3 is a cross section on the line C—D, Fig. 1;

Fig. 4 is a cross section on the line E—F, Fig. 1.

Referring to the drawings:—

a is the chimney stack, b the vent lining, and c an ordinary top or cowl. The improved cowl, as shown, comprises three parts 55 d, e, f, the part d being of combined globular and conic formation, the part e also of com-

bined globular and conic formation and the part f of globular formation with a depending pipe or flue. The part d is supported on the part e by means of a flanged ring g 60 in which four apertures h are made, and the part e is supported on the part f in a similar manner.

The part d has a globular body d¹ and a lower portion of flared or conic formation 65 d². d⁵ are apertures in the globular body, one at each side.

The part e has similarly a globular body e¹ and a flared lower portion e² with air escape apertures e⁵, one at each side. The 70 shape of the part e may, as shown, be slightly different from that of the part d.

The lower part f has a globular body f¹ and a tubular part f² the lower end of the tube fitting into the chimney vent. It has 75 apertures at opposite sides at f⁵. The various parts have restricted passageways or throats at d³, d⁴, and e³, e⁴, and f³, f⁴, respectively.

The part d may be surmounted by a top 80 h of truncated conic formation upon which the cowl e is fitted. The top is supported by a flanged ring g having apertures h therein.

For the purpose of supporting the structure and stiffening it against lateral wind pressure there may be metal standards or supports l connected with a supporting ring m.

It will also easily be understood that the 90 device described may be constructed and arranged to suit circumstances. For instance, the height from the ring m to the top of the cowl can be reduced considerably by building the tubular part f² entirely or nearly so 95 into the mason work of the chimney, and by lessening the height of the device to about four feet for residences, or increasing it for chimneys of manufacturing establishments, the vacuum caused in the middle globular 100 body is diminished or increased accordingly.

Having now fully described my said invention, what I claim and desire to secure by Letters Patent is:—

1. In the herein described chimney cowl, 105 the combination, with a plurality of superimposed parts of which the top and bottom part are provided with air escape apertures, one on either side, each of the said parts being of combined bulbous and conic formation and open at the top and bottom to form passageways, of means to support the several 110

parts on one another and on the chimney, all substantially as and for the purpose set forth and shown.

2. In the herein described chimney top, 5 the combination, with three superimposed parts having air escape apertures, of which the two top parts are of combined bulbous and conic formation and the bottom part formed into a globular body terminating in 10 a tube which fits into the chimney vent, and all the parts being open at the top and bottom to form passageways, of a top of truncated conic shape and surmounting the upper of the said three parts, an ordinary cowl

fitted on said top, flanged and holed rings 15 mounted in said passageways and supporting the superimposed parts, and means to support the whole structure on the chimney and stiffen said structure, all substantially as and for the purpose set forth. 20

In testimony whereof I have hereunto set my hand in the presence of two subscribing witnesses.

WILLIAM JOHNSON CALDER.
